[57] CLAIM

The ornamental design for a consumer scale mat, as shown and described.

DESCRIPTION

FIG. 1 is a top view of a present embodiment of the consumer scale mat of the present invention, an exemplary scale with which the mat may be associated being shown in phantom lines;

FIG. 2 is a left and right side view of the mat of FIG. 1; FIG. 3 is a partial sectional view of the mat shown in FIG. 1 along line 3—3;

FIG. 7 is a left and right side view of the mat of FIG. 6; FIG. 8 is a partial sectional view of the mat shown in FIG. 6 along line 8—8;

FIG. 9 is a front and rear view of the mat shown in FIG. 6; FIG. 10 is a bottom view of the mat of FIG. 6.
